UNITED STATES PATENT OFFICE.

JOHN R. ROGERS, OF BROOKLYN, NEW YORK, ASSIGNOR TO MERGENTHALER LINOTYPE COMPANY, A CORPORATION OF NEW YORK.

TYPOGRAPHICAL COMPOSING AND DISTRIBUTING MACHINE.

Application filed September 10, 1920. Serial No. 409,307.

To all whom it may concern:

Be it known that I, JOHN R. ROGERS, a citizen of the United States, residing at Brooklyn, in the county of Kings and State 5 of New York, have invented certain new and useful Improvements in Typographical Composing and Distributing Machines, of which the following is a specification, reference being had therein to the accompanying drawing.

My invention relates to typographical machines, such as linotype machines of the general organization represented in Letters Patent of the United States to O. Mergenthaler No. 436,532, wherein the circulating matrices are released from a magazine or magazines in the order in which their characters are to appear in print and then assembled in line, the composed line transferred to the face of a slotted mold, the mold filled with molten metal to form a slug or linotype against the matrices which produce the type characters thereon, and the matrices thereafter returned through 20 distributing mechanism to the magazine or magazines from which they started. More particularly, it relates to machines of the kind covered by my prior Letters Patent No. 1,270,328, and contemplates certain improvements in the different parts of such machine, as will be fully set forth in the detailed description to follow.

In the accompanying drawings, I have shown my invention only in preferred form 35 and by way of example and as applied to the style of machine above particularized, and it will be understood that many changes and variations in its form and in its mode of application may be made and 40 still be comprised within its spirit. Generally speaking, I desire it to be understood that I do not limit myself to any specific form or adaptation except in so far as such limitations are specified in the claims.

Referring to the drawings:

Fig. 1 is a front view of a portion of a linotype machine having my invention applied thereto:

Fig. 2 is a side elevation thereof looking 50 from the right in Fig. 1:

Fig. 3 is an enlarged vertical section taken through the supplemental assembling mechanism, etc.:

Fig. 4 is a rear elevation of the font se-

lecting devices for the supplemental magazines:

Fig. 5 is an enlarged vertical section of the supplemental escapement actuating devices:

Fig. 6 is a plan view of the upper pair 60 of supplemental magazines with certain parts broken away, and illustrating the manner in which the magazines are removably supported in the machine:

Fig. 7 is a top plan view of the supplemental assembling devices, and illustrating the driving connections for the matrix conveying belts:

Fig. 8 is a diagrammatic view of the supplemental magazines and the associated 70 distributor bars and keyboard connections, illustrating the general relationship of these parts:

Fig. 9 is a comparative view of two different matrices of an auxiliary font. 75

The matrices of the regular fonts are stored in the series of main stationary magazines A, four of which are illustrated herein, although a greater or less number may be employed if desired. The release of the matrices from the magazines is controlled by the keyboard A¹, which may be operatively connected to any desired magazine by the operation of the hand lever A⁹. As the matrices are released, they pass down 80 or through the channelled raceway or front plate A² onto the conveyor belt A³, which delivers them to the customary assembler wherein they are composed in line. After composition, the line is transferred to the casting mechanism for the production of the slug, and then carried upward and delivered to the so-called primary distributor B (see Fig. 2), which sorts the matrices according to form, and irrespective of character, and drops them into one or another of the tubes B¹ leading to the main distributing mechanism which separates the matrices according to character and drops them into the appropriate channels of the 90 underlying magazine entrances B³ leading to the respective magazine A. The main distributing mechanism is made up, as usual, of longitudinal ribbed or permuted bars B², one for each magazine, and a set 95 of conveying screws B⁴ for propelling the matrices therealong. The parts so far described are as embodied in the well known

100
105

"Model 9" linotype, but if desired reference may be had to my prior Letters Patent No. 848,771 which illustrates many of the details.

The matrices of the auxiliary fonts are stored in the second series of stationary supplemental magazines C arranged at the side of or in tandem with the main magazines A and of the same number although 10 not necessarily so. These supplemental magazines are of plain rectangular shape and have their grooved channels parallel throughout and more widely separated than those of the main magazines in order to accommodate the larger matrices which they 15 are intended to contain, each magazine being provided with 33 different matrix channels. To provide for the distribution of the matrices into the supplemental magazines 20 C, the main distributing mechanism (see Fig. 1) is extended sufficiently for that purpose, further magazine entrances C¹ being employed to conduct the matrices from the extended portion of the distributing mechanism 25 to the respective magazines. In other words, the several distributor bars B² and their conveying screws B⁴ are made long enough to cooperate with both series of magazines, each bar alone serving the opposite magazines of the two series. The exact manner in which this is accomplished 30 will be pointed out later in the discussion of my improvements.

Referring now to the assembling mechanism for the supplemental magazines C, it will be noted (Figs. 1 and 3) that each has associated therewith a separate endless conveyer belt F, the lowermost belt being extended to the left and constituting in effect 35 a continuation of the main assembling belt A³, and the three upper belts communicating with the main belt through tubes or conductors G which are arranged to discharge the matrices on to the extended portion of the lowermost belt F. These belts F are arranged one above another and are disposed horizontally along the discharge ends of their respective magazines in position to receive the matrices therefrom, the matrices 40 being guided to the belts by the short intermediate channeled throats E. In connection with each belt, there is provided an angular plate E¹ whose horizontal portion extends beneath the belt to prevent sagging and 45 whose vertical portion is arranged in front of the belt to assist in guiding the matrices as they are carried to the left thereby. In order to avoid any interference with the matrices and the other parts, the several 50 belts F are so arranged that notwithstanding their superposed relation, the overlying ones will be adequately spaced from the underlying ones. As shown in Fig. 1, each belt 55 is supported at its opposite ends upon the pair of rollers F¹ and with its lower stretch

passing over the second pair of guide rollers F² which maintain the lower stretch of the belt in closed proximity to although out of contact with the upper stretch, thereby providing ample space for the matrices as they 70 pass onto the belts from the magazines. The extended portion of the lower belt is supported in a similar manner, it being noted (Fig. 1) that further rollers F³ and F⁴ are employed for that purpose although the latter roller is made use of only to maintain the lower stretch of the belt free and clear of the upper end of the hand lever A⁹ before referred to.

The release of the matrices from the supplemental magazines C is controlled by the several series of escapements C² which are actuated in one direction by the springs C³ and in the opposite direction through the intermediate pivoted levers H¹ by the vertically movable reeds or operating devices H² slidably supported in the comb plates H⁶ and constantly urged upwardly by the attached springs H⁵. The reeds H² are in turn actuated from the separate and independent 90 keyboard H, which in the present instance comprises a series of horizontal centrally pivoted finger keys H⁴ extending diagonally toward the main keyboard A¹ and whose actuating movements are imparted to the vertical reeds H² through small pivoted levers H³. In the normal condition of the parts, the escapements C² are held by the springs C³ with their upper pawls in engagement 95 with the leading matrices in the corresponding magazine, the levers H¹ being held away from the escapements by the springs H⁵ which maintain the reeds H² in raised position. When, however, the finger keys H⁴ are actuated, they through the levers H³ depress the reeds H² against the action of the springs H⁵ and thereby cause the levers H¹ to rock the escapements C² to their reversed position. This action of the parts effects the withdrawal of the upper escapement pawls 100 from the magazine and allows the matrices to slide forwardly until they are arrested by the lower pawls, which by the same action have been projected into the magazines. Then, when the finger keys H⁴ are released, 105 the springs C³ and H⁵ restore the parts to their former condition, effecting the withdrawal of the lower pawls to allow the matrices momentarily arrested thereby to pass from the magazine, and at the same 110 time projecting the upper pawls into the magazine to arrest the next matrices, which now become the leading ones.

Each of the auxiliary fonts is divided between two magazines, the two upper ones 115 containing one font, half in one and half in the other, and the two lower ones the other font, one half in each. Due to this division of the matrix fonts among the supplemental magazines, means are provided (as herein- 120

after to be described) whereby the keyboard H may be operatively connected at will to either pair of magazines to the exclusion of the other. To permit the operation of the 5 escapements of both magazines at the same time, the magazines of the selected pair have their matrix channels arranged in staggered relation to each other (see Fig. 8) so as to locate the escapements of the respective 10 series in different vertical planes or in a correspondingly staggered relation. As thus arranged, the escapements of the upper magazine through their pivoted levers H¹ may be connected to every other one of the 15 key-controlled reeds H², while the escapements of the next lower magazine, through their corresponding levers H¹, may be connected to the intermediate reeds. In other words, the key controlled reeds are in effect 20 divided into two alternated sets, one connected to the escapements of the upper magazine and the other to the escapements of the next lower magazine. For instance, as shown in Fig. 8, the actuation of the first, 25 third and fifth of the reeds will effect the operation of the first, second and third escapements of the upper magazine and the consequent release of the matrices bearing the characters "e", "a" and "i"; while the 30 actuation of the second, fourth and sixth of the reeds will effect the operation of the first, second and third escapements of the lower magazine and the consequent release of the matrices containing the characters "t", "o" 35 and "n". The two magazines of the lower pair are arranged in the same manner, their respective escapements being staggered with reference to each other and connected through the pivoted levers H¹ to the alternate 40 sets of the key controlled reeds H², it being understood that for this purpose the escapements of the lower pair are located in the vertical planes of the corresponding escapements of the upper pair.

45 The foregoing parts and their mode of operation, except as herein noted, are or may be substantially the same as set forth in my Letters Patent No. 1,270,338 before mentioned. As before stated, the present 50 invention is directed primarily to certain improvements in the patented machine, and these will now be taken up in detail.

In my Letters Patent just mentioned, the 55 means employed for selecting either pair of supplemental magazines include locking devices attached to the respective magazines and which are operated under the control of font-selecting finger keys in such manner that the actuation of one key effects the un- 60 locking of the matrices in the corresponding pair of magazines and the locking of the matrices in the other pair of magazines. My present improvements are intended to do away with these locking devices and to 65 provide for the selection of either pair of magazines in a different and more advantageous manner. As shown in Figs. 3 and 5, the levers H¹ before mentioned are pivotally mounted upon transverse supporting rods J, 70 one for each series, it being noted that the levers are formed in their bottom edges and midway of their length with open bearing notches h which fit over the supporting rods and which have their rear walls straight as shown. Each of the supporting rods J 75 is flattened or recessed at one side, as at j, and is mounted at its opposite ends in suitable bearings so as to be turned or adjusted angularly to face the recess j toward or away from the straight rear walls of the 80 bearing notches h, as desired. In the latter position of the supporting rod, as indicated in the lower part of Fig. 5, the pivoted levers H¹ are maintained in operative relation to the corresponding series of escapements C², that is to say, in such position that when turned or rocked about the rod by the depression of the reeds H² (see the dotted lines), their rear ends engage the lower 85 ends of the escapements and actuate the same to effect the release of matrices from the magazine in the customary way. In the other position of the supporting rod, however, as shown in the upper part of Fig. 5, the pivoted levers H¹ are maintained in inoperative relation to the corresponding series of escapements C², being caused when 90 rocked about the rod by the depression of the reeds H² (see the dotted lines) to fall forwardly and downwardly away from the 95 escapements to such extent that their rear ends do not strike the escapements and hence fail to actuate the same. In short, the arrangement is such that by adjusting the supporting rods J to one position or the other, 100 the pivoted levers H¹ will be located in an operative or inoperative position, as required. In this way, the connection between the finger keys H⁴ and the escapements C² 105 may be made or broken at will to provide for 110 the release of matrices from any desired pair of magazines.

Since the magazines C are to be used in pairs, as just indicated, it is desirable that the supporting rods J be correspondingly 115 adjusted in pairs in selecting the desired magazines, and means are therefore provided to effect their adjustment in this manner, such means including connections whereby the adjustment of the supporting 120 rods of one pair to one position effects the adjustment of supporting rods of the other pair to the reverse position, and vice versa, so as thus to establish an operative connection between the keyboard H and either pair 125 of magazines. As herein illustrated, the magazine selecting means (see particularly Fig. 4) comprise two vertical reciprocating rack bars J² arranged side by side and meshing with pinions J¹ attached to the in- 130

ner ends of the adjustable rods J, the pinions on the two pairs of rods being located in different vertical planes to provide for such meshing engagement. The rack bars 5 J² are connected by means of vertical links J³ to the rear ends of a pair of centrally pivoted finger keys J⁴, arranged at different levels and provided with inwardly extended arms J⁵ which are jointed together 10 at an intermediate level, as at J⁶. As a result of this arrangement, when either one of the finger keys is depressed to effect the raising of the attached rack bar J², the other finger key is rocked in the opposite direction to depress its particular rack bar, thereby turning the supporting rods of the two pairs in reverse directions and consequently effecting the operative connection of the keyboard H in the manner before described with 15 one or the other pair of magazines according to the key depressed.

There will be times when it is desirable to lock the finger keys of the supplemental keyboard against actuation; and as a simple and 20 convenient way to accomplish this result, I employ a longitudinally adjustable locking bar K (Figs. 1, 3 and 7) mounted upon the lowermost comb-plate H⁶ and adapted to be shifted edgewise into and out of rectangular notches h² formed in the forward edges of the reeds H². Such edgewise shifting of the bar is effected by means of cam slots K¹ (Fig. 7) formed in the bar and cooperating with headed pins or studs K² screwed into the comb plate and which serve to hold the bar in place thereon. Hence, to lock or 25 unlock the keyboard H, the operator has merely to shift the bar K to the right or left as the case may be, it being noted that the bar is located within easy reach of the operator while seated at the machine and accessible at all times.

In my said Letters Patent No. 1,270,328, the major portion of the assembling mechanism for the main magazines A is carried by 30 the supporting frame N which is arranged to be swung outwardly toward the right about the vertical pivot rod N¹, and the assembling mechanism for the supplemental magazines C including the throats E, belts F, tubes G, keyboard H, font selecting keys J⁴, with their various appurtenant parts, and in fact all of the assembling devices immediately associated with the magazines, are 35 carried by the further supporting frame M which is mounted to be swung to the left about the same pivot rod N¹. In the present arrangement, however, the frame M is mounted to turn about a separate pivot rod M¹ disposed at the right of the machine, so that 40 the frame may be swung outwardly toward the right away from the main assembling mechanism. This arrangement has been found more advantageous than the former 45 for a variety of reasons and particularly as

it avoids any interference between the two swinging frames and allows both to be opened wide at the same time when that becomes necessary. The frame M is locked in its normal closed condition by the pivoted latch M² (Fig. 7), being accurately located in such position by the aligning piece M³. 70

It is again noted, as a feature of the present invention, that the conveyer belt F associated with the lowermost supplemental magazine C is separate and distinct from the main conveyor belt A³, which latter in my prior construction was extended to the right sufficiently to receive the matrices directly from that magazine. This change has 80 been made to permit the frame M to be swung outwardly at any time without disturbing the belts or removing them from their pulleys, as was previously necessary in the case of the main assembling belt. On 85 the contrary, in the present arrangement, the lowermost belt F is arranged to be moved into and out of operative relation to the main belt A³ as the frame M is opened and closed, respectively. In this connection, it 90 may be noted that the space between the upper surfaces of these two belts when in operative relation is bridged by a curved throat G³ attached to the frame N and which conducts the matrices from one belt to the other, 95 the throat containing a thin flexible leaf spring G⁵, as shown in Fig. 1. It may also be noted at this point that the tubes G before referred to contain similar springs G¹ extending throughout the length thereof and 100 are also provided at their lower or discharge ends with further springs G² which overlie the extended portion of the lowermost belt F. These various leaf springs not only serve to 105 guide and control the matrices (thick or thin) in their travel to the main belt A³ but also act to cushion the impact of the matrices against the upper walls of the tubes G and throat G³ as they enter the latter from the supplemental belts F. 110

My improved devices for driving the supplemental belts F will next be described, reference being made particularly to Figs. 1, 2 and 7. As best shown in Fig. 2, the shafts of the series of pulleys F¹ located to the right are connected together at the rear so as to rotate in unison and in the same direction by a sprocket wheel and chain arrangement F⁵, which has associated therewith tension rollers F⁶ acting upon the outer stretch of 115 the chain to hold its links in engagements with the sprocket wheels. The shaft of the lowermost pulley of the series is provided at the front with a driven pulley F⁷ connected by belting F⁸ to a driving pulley F¹⁴ fast to the constantly driven "intermediate" shaft F¹¹, the belting passing over or around an intermediate series of guiding pulleys comprising the pair of vertically arranged pulleys F⁹, F¹⁰ attached to the swinging frame 120 130

M, the single double-grooved pulley F¹¹ mounted to rotate about an extension of the pivot rod M¹, and the angularly disposed pulleys F¹², F¹³, journaled in a fixed part of 5 the machine adjacent the driving pulley F¹⁴. According to this arrangement and by reason of the fact that the pulley F¹¹ is mounted concentrically to the pivotal axis of the swinging frame M, the latter is free to be 10 swung to and from operative position at will without affecting the driving connections,—a feature very advantageous for obvious reasons.

My invention also contemplates certain 15 improvements in the form and arrangement of the supplemental magazines C, which, it may be stated in passing, are of the short variety or of less than full length, being connected to the magazine entrances C¹ by 20 the intermediate conductors C⁴.

Since two distince magazines are devoted to each of the auxiliary matrix fonts as before described, in interchanging either of such fonts, it is necessary of course to 25 move both of the magazines wherein the different portions of that font are stored and to substitute another pair of magazines containing the new font. In my prior construction, this interchange of the matrix fonts in- 30 volved considerable time and labor due to the separate character of the magazines, which had to be removed and replaced independently; and, besides, it sometimes happened that the separate magazines contain- 35 ing different portions of the same font would become misplaced or confused with magazines containing portions of other fonts, thus resulting in an improper mixing of faces and occasioning further delay and an- 40 noyance in the use of the machine. In the present arrangement, and to overcome the above and other objections, the supplemental magazines C of each pair are connected together as a single structure, so that both may 45 be removed from or replaced in the machine by a single operation, and so that both por- tions of the contained matrix font cannot become separated or confused with portions of other fonts.

Referring particularly to Figs. 3 and 6, it will be noted that each magazine C, as customary, is provided on its underside with two transverse reenforcing bars C⁵, the front bar being extended beyond the opposite 55 edges of the magazines and engaging in longitudinal fore-and-aft grooves O¹ formed in the inner side faces of the frame members O, and the rear bar being seated upon the bridge plate O², which also gives support 60 to the corresponding conductor C⁴ at its forward end. The two upper magazines, which contain different portions of one of the auxiliary fonts, are connected rigidly together at their rear ends by transverse bolts C⁹ 65 passing through an intermediate spacing

block C⁸ which serves to maintain the two magazines in proper parallel relation; and the two lower magazines containing different portions of the other auxiliary font are connected together in like manner. To 70 hold the magazines in place in the supporting frame, there are employed two transverse locking devices D, one for each pair, which devices are slidale longitudinally upon the two further bridge plates O³ and 75 which are normally arranged in engagement with the forward ends of fore-and-aft bars C⁶ secured to the under sides of the lower magazines of the two pairs. When it is desired to remove either pair of magazines, 80 the corresponding locking device is withdrawn to the right out of engagement with or clear of the bar C⁶, in which position of the parts the two connected magazines as one are permitted to slide forwardly by 85 gravity from the supporting frame, being guided in a straight parallel path by the engagement of the extended portions of the bars C⁵ in the fore-and-aft grooves O¹ of the frame members. It will be understood 90 of course that in effecting such removal of the magazines, the frame M carrying the associated assembling mechanism is swung to one side out of the way.

My improvements also involve a new 95 scheme for distributing the matrices of the two auxiliary fonts into the supplemental magazines, which scheme is intended to permit the use for that purpose of the regular seven ribbed distributor bar. As is well 100 known, in order to distribute matrices bearing different characters into different magazine channels, it is the universal practice to allot one bar-combination to each character in the matrix font. Since the regular 105 matrix font comprises ninety different characters, it follows that the number of bar-combinations required for the distribution of such font must be at least ninety; the usual number is ninety-one due to the em- 110 ployment of an additional combination for an extra column of matrices bearing the letter "e". The greatest number of possible combinations for one distributor bar under the seven rib system is about one hundred 115 twenty-six, so that the number of additional combinations available for an auxiliary matrix font is usually thirty-five. Now it will be remembered that each auxiliary font herein employed comprises sixty-six dif- 120 ferent characters, so that the above number of additional combinations is entirely in- adequate for the distribution of such font in accordance with the old method. To overcome this difficulty, I propose to provide 125 the matrices of the two portions of each auxiliary font with the same tooth-combi- nations notwithstanding the different characters which they represent, otherwise dis- tinguishing them as to form to provide for 130

their separation according to group. As the matrices are thus formed, the number of bar-combinations required for the distribution of the auxiliary fonts is just half 5 the number of characters represented in each font, namely, thirty-three, which number therefore is within the limit above indicated. This will be entirely clear from the diagram of Fig. 8, wherein the bar combinations No. 10 90 and 91 are the last two of those employed for the distribution of the regular matrix fonts, while the bar-combinations No. 92, 93, and 94 and Nos. 122, 123, and 124 are the first and last three of those 15 employed for the distribution of the auxiliary fonts. These latter, as before explained, are divided among the magazines C, half of one auxiliary font (representing thirty-three different characters) being 20 stored in the upper magazine of each pair, and the other half (representing thirty-three further characters) being stored in the lower magazine of each pair. Taking either font, by way of illustration, the matrices of 25 the group in the upper magazine are formed with the same tooth-combinations as those of the group in the lower magazine. For example, in Fig. 9, there are shown two matrices one bearing the letter "e" and the 30 other the letter "t", which matrices (being stored in the first channels of the respective magazines) are formed with identical tooth combinations X^1 designed to cooperate with the ninety-second bar-combination, the first 35 of the additional series. These matrices however are distinguished from each other, by differently located notches X^2 formed in their lower ends and which are designed to cooperate in the well known manner with 40 the selecting bridges of the primary distributor B so as to cause the matrices to be delivered to different distributor bars and hence returned to their different magazines. The matrices stored in the second channels 45 of the two magazines (bearing the letters *a* and *o*) are likewise formed with one and the same tooth-combination although the latter of course is designed to cooperate with the ninety-third bar-combination. The 50 matrices in the remaining corresponding channels of the two magazines have their tooth-combinations arranged in a similar manner, it being understood always that the matrices of the two groups are distinguished 55 from each other by the presence of the differently located notches X^2 . It is seen, therefore, that while I have, contrary to the universal practice, provided matrices of a single font with the same tooth-combinations notwithstanding the different characters which they represent, nevertheless no possible harm or confusion can result therefrom because of the distinguishing notches X^2 which enables the matrices to select their 60 own particular magazine. 65

As a further feature in the general scheme of distribution, the two distributor bars associated with each pair of magazines have their combinations arranged in different vertical planes as indicated in Fig. 8, so as to 70 correspond to the staggered relation of the matrix channels in the respective supplemental magazines. The combinations for the main magazines are unchanged, they being arranged in the same vertical planes on 75 the different distributor bars as heretofore.

As in the commercial machines, the various parts of the main distributing mechanism are all mounted in a supporting frame B⁵ which is arranged to be swung upwardly 80 about the transverse supporting rod B⁶ to give access to the interior parts. Such movement of the swinging frame is ordinarily effected by hand, but in the present machine, the added weight of the parts due 85 to the extension of the distributing devices renders this more difficult. For this reason I have provided mechanical means to effect the raising and lowering of the supporting frame. Such means, in the embodiment illustrated, simply comprise a long hand lever P pivoted centrally to the frame work as at P¹ and connected to the distributor frame by a link P². By pushing the hand lever forwardly, the distributor frame will 90 be swung upwardly to the dotted line position indicated in Fig. 2, the parts being so proportioned that the hand lever is caused to pass "dead center" and thus lock the frame in its raised position. 95

While my various improvements have been herein described and illustrated in connection with a tandem magazine machine, they might be embodied to advantage in a machine equipped with one series of magazines either supplemental or main, or in any other machine to which the improvements would apply. It will be understood therefore that they are not limited in their employment to the particular kind of machine herein illustrated and described, although they play an important part in connection therewith. As previously stated, I show my invention only in preferred form and by way of example, and it will be obvious that many modifications or alterations therein will suggest themselves to those skilled in the art without departure from its scope. 110

Having thus described my invention, its 120 construction and mode of operation, what I claim is as follows:

1. In a typographical machine, the combination of a magazine provided with a series of escapements, a series of key-controlled operating devices, and intermediate pivoted levers serving by their pivotal movement to transmit motion from the operating devices to the corresponding escapements, the said levers being mounted so as 125

to be shiftable to operative or inoperative position, as required.

2. In a typographical machine, the combination of a magazine provided with a series of escapements, a series of key-controlled operating devices, intermediate pivoted levers serving by their pivotal movement to transmit motion from the operating devices to the corresponding escapements, and a supporting rod upon which said pivoted levers are mounted to turn, the said rod being adjustable to render the pivoted levers operative or inoperative, as required.

3. In a typographical machine, the combination of a magazine provided with a series of escapements, a series of key-controlled operating devices, intermediate pivoted levers for transmitting motion from the operating devices to the corresponding escapements and formed with bearing notches, and a supporting rod located within said bearing notches and flattened or recessed at one side, the said supporting rod being adjustable angularly to face its recessed or flattened side toward or away from the rear walls of the bearing notches so as to render the pivoted levers operative or inoperative, as required.

4. In a typographical machine, the combination of two superposed magazines each provided with a series of escapements, a common series of key-controlled operating devices, two series of intermediate pivoted levers for transmitting motion from the operating devices to the corresponding escapements of the two magazines, and means for establishing an operative relation between the pivoted levers of one series and their corresponding escapements and an inoperative relation between the pivoted levers of the other series and their corresponding escapements, and vice versa, as required.

5. In a typographical machine, the combination of two superposed magazines each provided with a series of escapements, a common series of key-controlled operating devices, two series of intermediate pivoted levers for transmitting motion from the operating devices to the corresponding escapements of the two magazines, supporting rods upon which the pivoted levers of the two series are mounted to turn and each adjustable to different positions to establish an operative or inoperative relation between its pivoted levers and the corresponding series of escapements, and connections between said supporting rods whereby the adjustment of one to one position effects the adjustment of the other to the reverse position.

6. In a typographical machine, the combination of two superposed magazines each provided with a series of escapements, a common series of key-controlled operating devices, two series of intermediate pivoted

levers for transmitting motion from the operating devices to the corresponding escapements of the two magazines, two selecting keys or equivalent devices, one for each magazine, and means whereby the actuation of either of said keys establishes an operative relation between the pivoted levers and the escapements of the corresponding magazine and an inoperative relation between the pivoted levers and escapements of the other magazine.

7. In a typographical machine, the combination of two superposed magazines each provided with a series of escapements, a common series of key-controlled operating devices, two series of intermediate pivoted levers for transmitting motion from the operating devices to the corresponding escapements of the two magazines, supporting rods upon which the pivoted levers of the two series are mounted to turn and each adjustable to different positions to establish an operative or inoperative relation between its pivoted levers and the corresponding series of escapements, two selecting keys or equivalent devices, one for each magazine, and means controlled by said keys for adjusting one of said supporting rods to one position and the other to the reverse position, and vice versa, according to the key actuated.

8. In a typographical machine, the combination of two magazines, and two centrally pivoted finger keys or the like for selecting one or the other of the magazines for use, the said keys being arranged at different levels and provided with inwardly extending arms jointed together at an intermediate level; whereby the actuation of either key restores the other to its original position.

9. In a typographical machine, the combination of two superposed magazines each provided with a series of escapements, a common series of key-controlled operating devices, two series of intermediate pivoted levers for transmitting motion from the operating devices to the corresponding escapements of the two magazines, supporting rods upon which the pivoted levers of the two series are mounted to turn and each adjustable to different positions to establish an operative or inoperative relation between its pivoted levers and the corresponding series of escapements, a pair of reciprocating bars connected to the supporting rods and each movable in opposite directions to turn the connected rod to its different positions, a pair of finger keys connected to the reciprocating bars, and connections between the finger keys whereby the actuation of either key effects the movement of the connected bar in one direction and the movement of the other bar in the opposite direction to reverse the positions of the two supporting rods, for the purpose described.

10. In a typographical machine, the combination of two pairs of magazines each provided with a series of escapements, a common series of key-controlled operating devices, a plurality of series of intermediate pivoted levers for transmitting motion from the operating devices to the corresponding escapements of the respective magazines, and means for establishing an operative relation between the pivoted levers and the escapements of one pair of magazines and an inoperative relation between the pivoted levers and the escapements of the other pair of magazines, and vice versa, as required.

15. 11. In a typographical machine, the combination of two pairs of magazines each provided with a series of escapements, a common series of key-controlled operating devices, a plurality of series of intermediate pivoted levers for transmitting motion from the operating devices to the corresponding escapements of the respective magazines, supporting rods upon which the several series of pivoted levers are mounted to turn and each adjustable to different positions to establish an operative or inoperative relation between its pivoted levers and the corresponding series of escapements, and means for adjusting one pair of supporting rods to one position and the other pair to the reverse position, and vice versa, as required.

20. 12. In a typographical machine, the combination of two pairs of magazines each provided with a series of escapements, a common series of key-controlled operating devices, a plurality of series of intermediate pivoted levers for transmitting motion from the operating devices to the corresponding escapements of the respective magazines, supporting rods upon which the several series of pivoted levers are mounted to turn and each adjustable to different positions to establish an operative or inoperative relation between its pivoted levers and the corresponding series of escapements, two font selecting keys or equivalent devices, one for each pair of magazines, and means controlled by said keys for adjusting one pair of supporting rods to one position and the other pair to the reverse position, and vice versa, according to the key actuated.

25. 13. In a typographical machine, the combination of an escapement, a finger key, and connections between the finger key and escapement, the said connections including a pivoted lever serving by its pivotal movement to transmit motion from the finger-key to the escapement and shiftable relatively to its pivot to make or break the connections, as required.

30. 14. In a typographical machine, the combination of an escapement, and means for operating said escapement, said means including a pivoted lever serving by its pivotal movement to operate the escapement and arranged to be shifted into or out of engaging relation to the escapement as required.

35. 15. In a typographical machine, the combination of an escapement, and means for operating said escapement, said means including a pivoted lever serving by its pivotal movement to operate the escapement and shiftable on its pivot in the direction of its length into and out of engaging relation to the escapement as required.

40. 16. In a typographical machine, the combination of a main magazine, assembling mechanism therefor including a matrix conveyor belt leading to the assembler, with a stationary supplemental magazine arranged at the side of the main magazine, and assembling mechanism therefor including a separate matrix conveyor belt forming a continuation of the main conveyor belt, together with a supporting frame whereon the supplemental assembling mechanism is mounted and arranged to be swung outwardly away from the associated stationary magazine, the said frame being adapted in its swinging movements to carry the supplemental conveyor belt into and out of operative relation to the main conveyor belt.

45. 17. In a typographical machine, the combination of a main magazine, assembling mechanism therefor including a matrix conveyor belt leading to the assembler, with a plurality of supplemental magazines, and assembling mechanism therefor including a plurality of separate matrix conveyor belts, one for each magazine, and the lowermost belt forming a continuation of the main conveyor belt and arranged to receive the matrices from the overlying belts, together with a supporting frame whereon the supplemental assembling mechanism is mounted and arranged to be swung outwardly away from the associated magazines, the said frame being adapted in its swinging movements to carry the supplemental conveyor belts into and out of operative relation to the main conveyor belt.

50. 18. In a typographical machine, the combination of a magazine, assembling mechanism therefor including a matrix conveyor belt, a pivoted supporting frame whereon the conveyor belt is mounted, and driving connections for said belt, the said connections including a driving pulley mounted independently of the swinging frame, a driven pulley carried by said frame, belting connecting the two pulleys, and an intermediate guide pulley mounted to rotate about the pivotal axis of the supporting frame so as to permit the latter to be opened or closed without disturbing the driving connections.

55. 19. In a typographical machine, the combination of a main magazine, a supplemental magazine arranged at the side thereof,

assembling mechanism cooperating with each magazine, and separate supporting frames upon which the assembling mechanisms of the respective magazines are mounted, the said supporting frames being arranged to be turned about independent pivots for the purpose described.

20. In a typographical machine, the combination of a main magazine, a stationary supplemental magazine arranged at the side thereof, assembling mechanism cooperating with each magazine, and a swinging supporting frame upon which the assembling mechanism for the supplemental magazine is mounted, the said supporting frame being pivoted at the right so as to swing outwardly away from the stationary supplemental magazine and away from the assembling mechanism of the main magazine.

20 21. In a typographical machine, the combination of a main magazine, assembling mechanism therefor including a matrix conveyor belt leading to the assembler, with a supplemental magazine arranged at the side of the main magazine, and assembling mechanism therefor including a separate matrix conveyor belt forming a continuation of the main belt, together with a swinging frame whereon the supplemental assembling mechanism is mounted, and driving connections for the separate conveyor belt thereon, the said connections including a driving pulley mounted independently of the swinging frame, a driven pulley carried by said frame, belting connecting the two pulleys, and an intermediate guiding pulley mounted to rotate about the pivotal axis of the swinging frame.

22. In a typographical distributing machine, the combination of two superposed magazines each formed with a series of matrix channels, those of one magazine being arranged in staggered relation to those of the other, and two associated distributor bars each formed with as many combinations as there are channels in the cooperating magazine, the said combinations being arranged in different vertical planes on the respective bars to correspond to the staggered arrangement of the magazine channels.

23. In a typographical machine, the combination of two superposed main channeled magazines, two superposed supplemental channeled magazines arranged at the side thereof, two distributor bars each serving both a main and a supplemental magazine and formed with as many combinations as there are channels in said magazines, the

combinations for the supplemental magazines being arranged in different vertical planes on the respective bars to correspond to the arrangement of the supplemental magazine channels.

24. In a typographical machine, the combination of two superposed main magazines containing regular matrix fonts, two superposed supplemental magazines arranged at the side thereof and containing different groups of one auxiliary matrix font, two distributor bars each formed with a series of combinations to serve a main magazine and with additional combinations to serve a supplemental magazine, and a primary distributor for delivering the matrices of the several fonts to one distributor bar or the other according to form, the matrices of each regular font being formed with tooth-combinations to cooperate with the main series of bar-combinations and which differ throughout the font, and the matrices of the auxiliary font being formed with tooth-combinations to cooperate with the additional bar-combinations and which are duplicated on the matrices of the two groups, substantially as shown and described.

25. In a typographical machine, the combination of a plurality of superposed magazines, distributing mechanism cooperating with all of the magazines, a supporting frame wherein said distributing mechanism is mounted and arranged to be swung upwardly away from the magazines, and means for effecting such movement of the supporting frame, said means comprising a hand lever pivoted to the machine frame, and a link connecting said hand lever to the supporting frame.

26. In a typographical machine, the combination of a plurality of superposed magazine, distributing mechanism cooperating with all of the magazines, a supporting frame wherein said distributing mechanism is mounted and arranged to be swung upwardly away from the magazines, and means for effecting such movement of the supporting frame, said means comprising a hand lever pivoted to the machine frame, and a link connecting said hand lever to the supporting frame, the said parts being so proportioned and arranged that the hand lever is caused to pass "dead center" in moving the supporting frame to its raised position and thereby lock the frame in such position.

In testimony whereof, I have affixed my signature hereto.

JOHN R. ROGERS,
